VAPOR PRESSURE CONTROL MEANS

Eugene H. Reid, Schenectady, N. Y., assignor to
General Electric Company, a corporation of
New York

Application July 25, 1931, Serial No. 553,135

3 Claims. (Cl. 250—27.5)

My invention relates to apparatus for transmitting power between alternating and direct current circuits through a space discharge device such as a mercury arc rectifier or inverter and its principal object is the provision of an improved means for controlling the vapor pressure in such space charge device whereby the load capacity of the device is increased.

In the operation of mercury arc devices particularly of high power it is of especial importance that the pressure of the vapor within the evacuated receptacle of the device be maintained constant at a predetermined value in all portions of the space within the evacuated receptacle. If this pressure is low the current which the vapor will carry is reduced; if on the other hand the pressure is too high danger of vapor breakdown arises. The mercury arc device operates, therefore, most efficiently only within predetermined comparatively narrow limits of vapor pressure and of temperature, and it is desirable that the cooling means which must be provided to absorb the heat losses incident to operation be so arranged as to maintain the vapor pressure within these limits.

Difficulties have been encountered heretofore, however, especially in certain high capacity mercury arc devices, in the control and equalization of vapor pressure in different portions of the space within the evacuated receptacle, these difficulties being due to the fact that in certain portions of this space appreciably more heat loss must be absorbed by the cooling means per unit space than in other portions, the cooling means as a whole thus being required to be distributed in such manner as to absorb much greater heat loss in these certain portions of the space within the device than in other portions.

In order to maintain the vapor pressure within the required narrow limits it is necessary not only that sufficient cooling and condensing surface be provided to absorb the total heat losses from the vapor but that a substantially increased amount of condensing surface per unit space be provided in those regions of the evacuated space within which the cooling and condensing means are most effective in the control of vapor pressure. It follows that in the usual mercury arc device, particularly for high current output, more condensing surface per unit of vapor space from which heat loss is to be absorbed is required in certain spaces within the tank or lower vacuum chamber proper than in other spaces, for example the space within the condensing dome, since more heat loss is to be

taken off per unit of space in this certain portion of the lower or tank space, through which the arc discharge passes from cathode to anodes, than in other regions. It is to be noted that the absorption of these higher heat losses is practically possible only in the region in which they arise since they can not be distributed to other regions and there absorbed, unless a high temperature gradient exists between the regions of high losses and of lower losses. Consequently, unless the heat absorbing means is in direct contact with the vapor in the space in which the above mentioned higher heat losses occur a relatively high vapor pressure will build up therein sufficient to cause failure of the vapor as a valve.

In accordance with my invention the above and other difficulties are overcome by the provision of additional cooling means in that region of the mercury arc device in which the absorption of heat losses is most effective in maintaining the vapor pressure within predetermined narrow limits, this additional cooling means including elements for conducting a cooling medium in the space adjacent the lower wall of the tank and the space adjacent the anode shield openings through which the arc discharge passes from the cathode to the anodes.

My invention will be better understood from the following description when considered in connection with the accompanying drawings and its scope will be pointed out in the appended claims.

Referring to the drawings, Fig. 1 is a cross-sectional view of a space discharge device embodying my invention, and Figs. 2 and 3 are curves illustrating the operation of a cooling system in accordance with my invention and of other systems, employed heretofore.

In Fig. 1 the space discharge device comprises an evacuated receptacle 10, a cathode 11 of vaporizable material such as mercury, and a plurality of anodes 12 of which one only appears in the drawings. The receptacle 10 includes a tank portion 13 having a side wall 14 and a lower wall or floor portion 15 concentrically arranged with reference to the cathode 11, and a condensing dome 16. The anodes 12 are arranged within anode housings or shields 17 which are mounted in the upper wall of tank 13 near the side wall 14 thereof and which are provided with openings 18 for the arc discharge between cathode and anodes. In order to absorb heat losses from the spaces within tank 13 and dome 16, cooling jackets 19, 20 are provided through which cooling medium 21 is circulated from any suit-

able source, and in order to increase the heat loss absorbing surface for the space above cathode 11 and within dome 16 coils 22 are mounted therein through which cooling medium circulates.

In the cooling system thus far described in connection with the space discharge device shown in the drawings the cooling medium enters the inlet pipe 23, thence passes to a cathode cooling chamber 24 arranged below cathode 11, to a cooling chamber 25 formed between the central portion of lower wall or floor portion 15 of tank 13 and the upper side of the cathode mounting member 26, through a pipe 27 to the coil 22 within dome 16, through the outlet 28 of coil 22 into the jacket 20, and through the outlet 29 of jacket 20 into a pipe 30. In cooling systems previously incorporated in the space discharge device shown in Fig. 1, and in similar space discharge devices, the cooling medium was discharged from pipe 30 into the extreme lower portion of jacket 19, being preferably connected for this purpose to a pipe 31 coiled around this lower portion of jacket 19 and having a plurality of orifices 32 to distribute the flow of the cooling medium into the jacket and thereby to avoid local overcooling of the wall 15. The cooling liquid was then discharged from the upper portion of jacket 19 through an outlet pipe 33.

In accordance with my invention, however, an additional heat loss absorbing means is provided for the space adjacent to the floor portion or lower wall 15 and below and adjacent to the openings 18 of the anode shields 17, this space being that through which the arc discharge from cathode 11 to anodes 12 passes to the openings in the anode shields. This additional heat loss absorbing means preferably includes a plurality of cooling medium conducting elements such as coils of pipe 34 preferably of relatively large diameter, certain of these coils, as 35, being mounted adjacent to the lower wall 15 of tank 13 and preferably spaced far enough from this wall to permit passage of vapor between coils and wall, certain others of the coils as 36 being mounted adjacent to the side wall 14 and the open ends of anode shields 17. The pipe 30, instead of being connected directly to the lower portion of jacket 19 through the pipe 31, as above described in connection with circulating systems heretofore employed in mercury arc devices such as shown in Fig. 1, is connected to the bank of coils 34, the cooling medium then circulating through coils 36 and 35, passing from coils 35 into the lower portion of jacket 19 through pipe 31 and out of the upper portion of the jacket into the discharge pipe 33.

It will be seen that the coils 34 constitute floor coils within the tank 13 so arranged as to form a cooling means, in addition to the cooling means provided by the lower portions of the walls of the tank in contact with cooling medium 21 in jacket 19, for absorbing heat losses in the space extending along the floor of the tank 13 to and along the side of the tank into the region adjacent to the openings 18 in the lower ends of the anode shields 17.

The operation of the above described improved system for control of the temperature and pressure within the evacuated receptacle 10 will be more clearly understood by reference to Figs. 2 and 3. The curves shown in these figures relate to the operation of mercury arc devices of the high power type illustrated in Fig. 1, having, for example, a capacity at full load of the order of

3000 kw. at 600 volts, normal load current being approximately 5000 amperes.

Referring particularly to Fig. 2, the curves therein in dotted line indicate in kilowatts the heat losses absorbed by the cooling means in a mercury arc device which is of the type shown in Fig. 1 but which is not provided with the cooling means represented by floor coils 34. In these dotted curves of Fig. 2 the curve marked "Tank" shows the loss taken off by cooling water circulating in jacket 19 in contact with the walls of the tank 13; the curve marked "Dome" shows the loss taken off by cooling water circulating in jacket 20 in contact with the walls of dome 16; and the curve marked "Coils over cathode" shows the loss taken off by cooling water circulating in a coil (not shown) similar to dome coil 22 but mounted centrally of receptacle 10 in the lower portion of dome 16.

Similarly the curves in full line in Fig. 2 indicate the heat losses in a mercury arc device of the type shown in Fig. 1 provided with cooling jackets 19, 20 and dome coil 22, and, further, with the additional cooling means represented by floor coils 34. The curves in this figure marked "To tank and coil", "To dome and coil" and "To cathode" indicate respectively the losses taken off by the cooling water circulating in jacket 19 in contact with the walls of tank 13 and also by the cooling water circulating in the floor coils 34; by the cooling water circulating in jacket 20 in contact with the walls of dome 16 and by the water circulating in dome coil 22; and by the water circulating adjacent the cathode 11.

It will be observed that these curves of Fig. 2 show that in both types of cooling systems above described, i. e., with and without the floor coils 34, considerably more heat loss occurs in the lower vacuum chamber than in other regions, for example the region within the condensing dome.

Referring to Fig. 3, the curves therein in dotted line indicate in watts the heat loss which must be absorbed per square inch of various cooling areas at different loads in a mercury arc device similar to that shown in Fig. 1 but not provided with the additional cooling means represented by floor coils 34. Thus the curve marked "Vacuum chamber proper" indicates the loss required to be absorbed, per square inch of that condensing area which is provided by the walls of tank 13, in order that the loss in kilowatts in this tank region and indicated by dotted curve marked "Tank" of Fig. 2 may be taken off by the cooling water. The curve in Fig. 3 marked "Coils over cathode" indicates the watts required to be absorbed, per square inch of the cooling coil similar to coil 22, mounted as above mentioned centrally of the receptacle in the lower portion of the dome, in order to take off the loss indicated by the curve marked "Coils over cathode" in Fig. 2. The curve in Fig. 3 marked "Dome" indicates the watts required to be absorbed, per square inch of the walls of dome 16, in order to take off the loss indicated by the curve marked "Dome" in Fig. 2.

The curves in full line in Fig. 3 indicate similarly in watts the heat loss which is required to be absorbed by each square inch of different cooling areas, for loads up to 150% full load, in the mercury arc device shown in Fig. 1 and having the above described additional cooling means in the tank space represented by floor coils 34. The curve in Fig. 3 marked "To tank and coil" indicates the loss required to be absorbed, per sq. in. of the combined cooling area provided by the

walls of tank 13 plus the area provided by the floor coils 34, in order to take off the loss in kilowatts indicated in the curve marked "To tank and coil" of Fig. 2. The curve in Fig. 3 marked "To dome and coil" indicates the loss required to be absorbed per sq. in. of the cooling area provided by the walls of dome 16 in contact with cooling water in jacket 20 and by the dome coils 22, in order to take off the loss in kilowatts indicated in the curve marked "To dome and coil" of Fig. 2. 5

10 Since the area of the cooling and condensing surfaces which is sufficient to maintain the vapor pressure within safe limits in high power mercury arc devices of the type herein described is approximately that area which provides one square inch of cooling surface per five watts of heat loss at 150% load, it will be apparent from Figs. 2 and 3 that, in the mercury arc device which is not provided with the floor coils 34 and to 15 which the dotted curves of these figures relate, the cooling surfaces provided for the absorption of the heat loss shown in kilowatts by the curve marked "Tank" of Fig. 2 are overloaded. This is evident since the curve marked "Vacuum chamber proper" of Fig. 3 indicates that even at 5000 amperes load, representing only normal full load, considerably more than five watts per square inch of cooling surface must be absorbed, in the mercury arc device not provided with the floor coils 20 34, by the tank walls in contact with cooling medium 21 in jacket 19. This overloading of the cooling surfaces in the tank region results in a rise of vapor pressure, tending to cause failure of the vapor as a valve, in the tank space including that space in the lower portion of the tank which extends adjacent the floor of the tank from the cathode chamber to the region of the lower open ends of the anode housings 17. 25

30 This latter space, through which the arc discharge passes from cathode to anodes, is more effective in holding vapor pressure at a predetermined value with load than other spaces, and it is in this space that I provide in accordance with my invention additional heat absorbing means, represented by floor coils 34, sufficient to 35 increase the total cooling surface preferably to double its former value and to lower the heat absorption per unit area of the cooling surfaces to a point well within the required minimum of five watts per sq. in. at 150% load, for example to four watts per sq. in. in the tank space at this load, as shown in curve marked "To tank and coil" in Fig. 3. This increase in the effective cooling surface in the tank region provided by floor coils 34 correspondingly decreases the heat absorption load imposed on the cooling surfaces in the dome region, the result being a better balance of the heat absorption per unit area in the entire space within the mercury arc device, as indicated by the curves of Fig. 3. 40

45 The above described additional cooling means in accordance with my invention, comprising the floor coils 34 mounted in that space which is most effective in controlling the vapor pressure, is particularly effective in condensing out mercury from the vapor blast issuing from the cathode and proceeding in the direction of the anodes, mercury being prevented thereby from penetrating to the hot region adjacent the anodes. 50 The condensing surfaces formed by the coils 34 do not, however, appreciably baffle or constrict the arc discharge between cathode and anodes although the arc passes close to these coils, which are mounted a sufficient distance from the adjoining walls of tank 13 to permit the 55

60 latter surfaces to function efficiently as cooling and condensing areas.

65 It will be observed that by the provision of the additional cooling means described herein as comprising the floor coils 34, mounted in the space in which cooling surfaces of given area are most effective in controlling vapor pressure, a marked increase in rating in a mercury arc device of given dimensions is obtained with a relatively simple and low cost added structure, a comparable increase in rating being obtained in mercury arc devices of the usual type only by an increase in the diameter and other dimensions of the evacuated receptacle and by an increase in the length of the arc stream between cathode and 70 anodes with a resulting objectionable increase in the arc drop, this being approximately $\frac{1}{4}$ volt for each inch increase in arc stream length. 75

75 It will be observed further that by the provision of the additional cooling means comprising the floor coils 34 danger of failure of the vapor as a valve particularly in the space between cathodes and anodes, wherein the heat loss per unit space is greatest, is minimized or eliminated at loads substantially higher than normal. 80

85 What I claim as new and desire to secure by Letters Patent of the United States, is:—

1. The combination with a space discharge device including a metal tank, a cathode, a plurality of anodes, a plurality of anode shields each 90 surrounding a different one of said anodes and each being provided with an opening at the lower end thereof adjacent the corresponding anode, a condensing dome mounted on said tank, means to circulate a cooling medium in contact with the 95 walls of said dome and means including cooling coils mounted within said dome to absorb heat losses therein, and means to circulate a cooling medium in contact with said tank to absorb heat losses in the space between said cathode and said 100 anode shield openings through which space passes the arc discharge between said cathode and said anodes, of auxiliary cooling means including cooling medium conducting elements mounted closely adjacent throughout their entire extent to the 105 lower wall portion of said tank in said space to increase the absorption of heat losses in said space to a predetermined rate of absorption, whereby the vapor pressure in said space between said cathode and said anode shield openings is 110 maintained at substantially the same value as that of the vapor pressure in said dome. 115

2. The combination with a space discharge device including a metal tank, a cathode, a plurality of anodes, and means to circulate a cooling 120 medium in contact with the lower wall portion of said tank to absorb heat losses in the space through which the arc passes between said cathode and said anodes, said cooling means providing substantially less than one square inch of 125 cooling area per five watts of heat loss in said space at 150% load, of auxiliary cooling means for said space including cooling coils mounted in said space closely adjacent said lower wall portion and extending to the region closely adjacent 130 to said anodes, the area of the cooling surface of said auxiliary means being such that the total cooling area for said space provides at least one square inch of cooling area per five watts of heat loss at 150% load. 135

3. In a space discharge device including an evacuated receptacle having therein a vaporizable cathode and a plurality of anodes each enclosed within an anode shield, the space in said receptacle above the lower end of said shields 140

requiring low absorption of heat loss per unit space, the space below said shield ends which constitutes the arc path between anodes and cathode requiring high absorption of heat loss per unit space, cooling means for said spaces including means to circulate cooling medium in contact with the lower side wall and floor portion of said receptacle, said cooling means absorbing said low heat losses in the first-named space without undesirable cooling in said first-named space, said cooling means being insuffi-

cient to provide said high heat absorption in said second-named space, and auxiliary cooling means mounted in said second-named space to add additional cooling area for the cooling of said second-named space to provide a total cooling area 5 for said second-named space sufficient to absorb the high heat losses therein and at the rate of substantially four watts per square inch at 150% load.

EUGENE H. REID. 10
